(57) CLAIM

The ornamental design for a headlight, as shown and described.

DESCRIPTION

FIG. 1 is a perspective view of a headlight showing our new design.

FIG. 2 is another perspective view thereof.

FIG. 3 is a front view thereof.

FIG. 4 is a rear view thereof.

FIG. 5 is a top view thereof.

FIG. 6 is a bottom view thereof; and,

FIG. 7 is a left side view thereof.

The part of the photograph shown in broken line with white, illustrates a portion of the headlight that forms no part of the claimed design.
